UNITED STATES PATENT OFFICE.

MARTIN JUREK, OF DALLAS, TEXAS.

REFRIGERATOR-DOOR.

1,382,837.

Specification of Letters Patent. Patented June 28, 1921.

Application filed February 15, 1921. Serial No. 445,086.

To all whom it may concern:

Be it known that I, MARTIN JUREK, a citizen of the Republic of Czechoslovakia, residing at Dallas, in the county of Dallas 5 and State of Texas, have invented certain new and useful Improvements in Refrigerator-Doors, of which the following is a specification.

This invention relates to new and useful 10 improvements in refrigerator doors.

In certain types of refrigerators a chamber containing several compartments and constituting the main storage portion, is closed by a single door; thus when it is desired 15 to remove a single article from one of the compartments the door must be opened which exposes all of the compartments and admits warm air thereto.

The object of my invention is to provide 20 an individual door for each compartment and disposed within the chamber; so that when the refrigerator door is opened none of the compartments will be exposed and whereby access to a compartment may be had 25 by opening the individual door thereto, without exposing the other compartments. Another object of the invention is to produce the compartment doors in the form of an attachment which may be applied to a refrigerator after the latter has been built or even after it has been in use.

A construction designed to carry out the invention will be hereinafter described together with other features of the invention.

35 The invention will be more readily understood from a reading of the following specification and by reference to the accompanying drawings, in which an example of the invention is shown, and wherein:

40 Figure 1 is a perspective view of a portion of a refrigerator equipped with a door attachment embodying my invention,

Fig. 2 is a horizontal cross-sectional view 45 of the refrigerator door, doorway and attachment,

Fig. 3 is a vertical sectional view on the line 3—3 of Fig. 2, and

Fig. 4 is a detail of one of the mullions.

In the drawings the numeral 10 designates 50 the doorway of a refrigerator which is stepped in the usual manner to receive the door 11. Within the inner margin of the doorway I mount a rectangular metallic frame 12 having a laterally and outwardly directed surrounding flange 13 overlapping 55 the face of the innermost shoulder 14 of

the doorway. The frame is held in place by means of narrow metallic strips 15 nailed in the angle at the intersection of the shoulder 14 with the next shoulder. These strips 60 not only hold the frame but give the attachment a finished appearance.

The frame has an angular channel 16 extending therearound and projecting into the refrigerator storage chamber. Rubber or 65 other packing strips 17 are confined in this channel. The storage chamber is divided by horizontal shelves 18 into superposed compartments 19. At the front edge of each shelf, a mullion channel 20 is provided and 70 carries a packing strip 21 of rubber or other material. The channels 20 have their ends fastened to the channel 16.

For each compartment an individual door 75 is provided and each door includes a frame 22, which may be of any suitable construction, but which I prefer to form of sheet metal bent upon itself to form an outwardly directed flange 23 and angular bezel 24 receiving the edge of a glass or other transparent plate 25. A keeper frame 26 engages over the frame 22 and overlaps the edge of the glass plate. The frames 22 and 26 are fastened together by screws 27.

Each door frame 22 has hinges 28 fastened 85 thereto and secured to one side of the frame 12, whereby the doors are hinged in front of the compartments. The doors swing into the channel 16 so that their extended flanges 23 overlap the faces of the packing strips 90 17 and 21. Spring handles 29 fastened on the doors engage knobs 30 on the frame 12, thus holding the doors closed.

It will be seen that when the compartment doors are closed, each compartment 19 is 95 thoroughly closed by its door and the contents of each compartment may be readily observed through the glass plate 25 of its door. When the chamber door 11 is opened all the compartments are exposed to view, but none is exposed to the warm air until 100 its individual door is opened. When it is desired to remove an article from any one compartment, it is merely necessary to open the individual door thereto. This can be 105 done without opening the other compartments as is obvious.

Various changes may be made in the construction and dimensions without departing from the spirit of the invention.

What I claim, is:

1. The combination with a refrigerator

having a main door opening, and a main door to close said opening, of an attachment frame arranged within the main door opening and formed separate therefrom, means 5 for securing the attachment frame to the wall of the main door opening, and a plurality of individual doors pivotally mounted upon the attachment frame.

2. The combination with a refrigerator 10 having a main door opening, the walls of said opening being stepped, and a main door to close the main door opening, of a separate attachment frame having its wall stepped in cross section and fitting upon the inner 15 portion of the stepped wall of the said main opening, means to secure the separate frame to the stepped wall of the main opening, individual doors hinged upon the separate frame, and means to hold the individual 20 doors closed.

3. In a refrigerator door construction, an attachment frame adapted to be arranged within the door opening of a refrigerator and having its material bent to form a channel 25 extending around the attachment frame, a packing strip held within the channel and having its forward side exposed, a plurality of mullion channels extending transversely within the main frame and secured thereto, 30 packing strips within the mullion channels with their forward sides exposed, and individual doors hinged to the attachment frame

and having portions thereof engaging the forward exposed sides of the said packing strips. 35

4. In a refrigerator door structure, an attachment frame adapted for arrangement within the inner portion of a refrigerator door opening and having its material bent upon itself providing a channel extending 40 about the attachment frame, said channel being adapted for arrangement inwardly of the door opening and having its forward side open, a packing strip held within the channel and having its forward side exposed, a plurality of mullion channels extending across the attachment frame in spaced relation and secured thereto, packing strips held within the last named channels, a plurality of individual doors, each individual door embodying a frame formed of sheet metal bent upon itself to provide a flat frame portion adapted to engage with said packing strips, a co-acting flat frame portion arranged opposite the first named 50 flat frame portion, a section of transparent material held between the inner portions of the flat frame portions, means for pivotally mounting each individual door upon the attachment frame, and means to retain each 55 individual door closed. 60

In testimony whereof I affix my signature.

MARTIN JUREK.
